[57] CLAIM

The ornamental design for a combined mast assembly with yarn tension and cutter gate and threading hook units for creels, substantially as shown and described.

DESCRIPTION

FIG. 1 is a top front and right side perspective view of a combined mast assembly with yarn tension and cutter gate and threading hook units for creels, showing my new design;

FIG. 2 is a top front left side perspective view thereof; FIG. 3 is a bottom rear and right side perspective view thereof;

FIG. 4 is a top plan view thereof;

FIG. 5 is a bottom plan view thereof;

FIG. 6 is a left side elevational view of the top fragmentary portion of that shown in FIG. 1;

FIG. 7 is a front elevational view thereof;

FIG. 8 is a right side elevational view thereof; and

FIG. 9 is a rear elevational view thereof.

FIGS. 1-3 are fragmentarily shown and broken away to show indeterminate length.

FIG. 1

FIG. 2
